UNITED STATES PATENT OFFICE.

EDWIN S. BROTHERS, OF BROOKLYN, NEW YORK.

WATER MOTOR.

Application filed May 25, 1926. Serial No. 111,496.

This invention relates to water motors and the general object of the invention is to provide a simple, economical and highly efficient construction adapted to be operated 5 from a faucet and capable, in turn, of operating small tools and appliances, such, for example, as a dental tool.

From a more specific standpoint, it is the object of the invention to provide a construction 10 wherein the parts can be economically manufactured from sheet metal, so as to render the manufacturing operations susceptible of being carried out by sheet metal stamping and forming dies. To this end, 15 the parts are so constituted that they may be readily stamped and formed by dies and thereafter assembled in an efficient and economical manner.

An important feature of the invention resides 20 in the novel form of rotor which constitutes a salient feature of the invention. This rotor is struck up in a die from a sheet metal blank in such manner as to form in the blank a series of radial corrugations, the 25 faces of which corrugations serve in practice as the vanes of the rotor. The construction of a rotor in this manner is not only desirable from the standpoint of economy, but has the further advantage of producing a 30 rotor of high efficiency and wherein the vanes are firmly supported throughout. By this arrangement, moreover, the weight of the rotor is minimized.

It is further characteristic of a rotor constructed 35 as described that it is reversible. That is to say, it may be driven from jets directed against the vanes in either direction.

The housing for the rotor is preferably made 40 in the form of two complementary sheet metal sections adapted to be brought into cooperative relation and thereafter a portion of one may be spun over a portion of the other to permanently assemble the parts.

The direction of rotation of the rotor is controlled by a water switching member 45 adapted to be manually operated to direct a jet against the vanes of the rotor in the direction appropriate to the desired direction of rotation of such rotor. This water switching member is positioned within the inlet end of the casing and is also of sheet metal construction capable of formation in suitable stamping and forming dies.

50 Features of the invention, other than those adverted to, will be apparent from the here-

inafter detailed description and claims, when read in conjunction with the accompanying drawings.

The accompanying drawing illustrates one 60 practical embodiment of the invention, but the construction shown therein is to be understood as illustrative, only, and not as defining the limits of the invention.

Figure 1 is a face view of a water motor 65 embodying this invention with one section of the casing removed.

Figure 2 is a section on the line 2—2 of Figure 1.

Figure 3 is an edge elevation of a rotor. 70

Referring to the drawings, 1 designates the rotor of a motor. It is, in practice, of sheet metal, stamped and formed by suitable dies into radial corrugations. The corrugations are so formed as to provide a series 75 of radially extending inwardly tapering vanes 2, the surfaces of which are substantially plane throughout the greater portions of their extents and which planes extend radially and are substantially parallel to 80 the axis of the rotor. The best results are obtained when the planes which include the vanes 2 also include the axis of the rotor. The successive main vanes 2 are by this formation connected by supplementary vanes 85 3, the planes of which may be made to occupy substantially the same relation to the axis of the rotor as the planes of the vanes 2. By making the curves at which the vanes 2 and 3 join one another relatively large, I 90 find that satisfactory results are obtained if the planes of the supplemental vanes 3 are in angular relation to the axis of the rotor as will be apparent from Figure 3. This arrangement facilitates the manipulation of 95 the metal and permits a somewhat wider vane than would be possible with the other arrangement.

The central portion of the rotor is as shown in Figures 1 and 2 substantially flat 100 and in the center of this flat portion is an aperture to receive a shaft. When forming the aperture, the margin thereof is preferably struck up slightly, as shown at 4 in Figure 2, to provide a boss imparting increased thickness at the aperture. The rotor is mounted on a suitable shaft or spindle 5, one end of which is reduced, as shown at 6, to provide a shoulder 7.

The rotor is slipped upon the reduced 110 portion 6 with a washer 8 between the rotor and the shoulder 7. A washer 9 is thereaf-

ter placed against the outer face of the rotor and the end of the reduced portion 6 thereafter upset or headed over, as shown at 10, to tightly clamp the parts in permanent relation to the spindle. During the operation of heading over the end of the spindle 5, a depression 11 is formed in such head and this depression constitutes a bearing as will be hereinafter more fully described.

The rotor is operable within the casing embodying two sections 12 and 14. These sections are, in the main, of complementary shape, so as to conform, generally, to the cross sectional contour of the rotor. The section 12 is provided with a peripheral wall 15, the free edge of which is in the form of an upwardly flared flange 16, while the outer margin of the section 14 is adapted to be spun or wiped over the flange 16, as shown at 17, for the purpose of permanently securing the parts together.

The section 12 is provided centrally with a laterally extending portion 18, centrally perforated to receive the reduced shank of a bearing 19 and the free end of the reduced shank is spun over to clamp the section 12 tightly to said bearing. The spindle 5 extends through the bearing and is rotatable therein. The section 14 is provided centrally with an outwardly extending portion 20 at the center of which is an inwardly extending projection 21 adapted to seat in the depression 11 and form a bearing for the free end of the spindle.

Inwardly extending beads 22 are formed on both sections and adapted to cooperate with the flat portion at the center of the rotor to limit the end play of the rotor and provide for proper clearance between the rotor and the respective sections 12 and 14.

Positioned in one end of the casing is a partition 23 forming beyond such partition a water chamber 24 having outlets 25, 25' at its opposite sides and through which outlets water from the chamber 24 is adapted to be directed against the vanes of the rotor. Water is fed to this chamber through a thimble 26, both ends of which are reduced.

The inner end extends through a perforation in the wall 15 of the casing section 12 and is spun outwardly to tightly secure the thimble to said section. With the other reduced end of the thimble 26 is similarly secured a sheet metal holder 27, the distant side of which is provided with an opening 28. Within the shell 27 is positioned two coaxial tapered sleeves 29 and 30. The sleeve 29 is employed if the motor is used with a small faucet, but is removed to permit the motor to be placed on a large faucet. In this manner, a detachable union between the faucet and the chamber 24 is produced.

Operable within the chamber 24 is a water switching member 31. This constitutes in

effect a valve. It is constructed from sheet metal and embodies a substantially segmental portion 32 at the periphery of which is formed a flange 33. The flange bears against the walls of the casing and the partition 23 and the resilient or springy character of such partition holds the switching member against lost motion.

When the switching member is in the position shown in full lines in Figure 1, water entering the chamber 24 through the nipple 26 will be directed through the opening 25' to drive the rotor in one direction and when the switching member is in the dotted line position of Figure 1, water will be directed through the opening 25 to drive the rotor in the other direction.

The switching member is operated by a suitable handle 34 positioned on the exterior of the casing section 12, the parts being locked together by means of a rivet 35. Figure 2 clearly shows the construction. The rivet is squared at both ends with an intermediate cylindrical portion. These squared ends cooperate with the valve and handle and are headed over to lock the parts together and at the same time preclude rotation between said parts. Washers 36 are utilized to minimize friction.

If it be assumed that the switching member is in the full line position of Figure 1, it will be apparent that water will issue from the opening 25' in the form of a jet which will be directed against such vanes of the rotor as are within the path of the jet. The parts are so designed as to direct the jet in a proper direction, whereby it is caused to impinge the vanes 2 in succession. As a matter of fact, the jet will impinge more than one of the vanes 2 at a time and will accordingly impinge the intermediate vane or vanes 3, so that there is an appreciable overlap exerting a driving force not only on the vanes 2, but also upon one or more of the vanes 3. This is in marked contradistinction to general practice and results from the employment of the novel form of rotor which I have described. There is thus not only driving power exerted against the main vanes, but also against the supplemental vanes.

Another important feature resides in the fact that the openings 25 and 25' are shaped to efficiently direct the jet upon the vanes. That is to say, one end wall of each of these openings or slots is substantially tangential to the rotor, while the opposite end wall is cut on an angle to the first end wall, so as to approach a radius extending from the center of the rotor through the opening. By this arrangement, the opening or slot flares in an outward direction, so that the jet is fanned. Thus, the vanes of the rotor come into cooperative relation with the jet in a gradual manner and leave cooperative

relation with the jet in like manner, there being a steady building up and falling off of the forcing of the jet during this operation with respect to any particular vane. 5 This is in pronounced contradistinction to prior constructions wherein the blade comes into cooperation with and is suddenly subjected to the full force of the jet whereby there is produced great sudden strains and 10 noise. The rotor of the present invention operates noiselessly for the reasons which I have set forth.

In practice, the motor is operated with the inlet end of the casing upright, and the 15 rotor is constructed with relatively little clearance between it and the walls of the casing, so that even after the force of the water is spent, its weight will assist in turning the rotor. The water is discharged from 20 the casing through an outlet or discharge opening 37 at the bottom thereof.

In all prior water motors of which I am aware, it has been the practice to feed the water directly from the faucet through a 25 nozzle to the vanes. By the present invention, however, the water is fed into the supply reservoir 24 where a body of water is maintained at all times under the pressure induced from the faucet. By this arrangement, a more steady supply is obtained and a more flexible control is provided. This 30 will be apparent when it is borne in mind that when the faucet is opened to allow water to flow into the reservoir, it will 35 start to flow from the opening 25' before pressure is built up in such reservoir and as such pressure builds up, the strength of the jet will be slowly built up and there will be a gradual starting action imparted 40 to the rotor instead of a sudden crash of the water against the vanes as is the case in prior constructions.

It will be apparent from the foregoing 45 detailed description that the elements of construction which constitute the motor of this invention are of extremely simple construction. They are susceptible to economical manufacture by stamping and forming dies and the assembly of such parts is such 50 as to enable these operations to be carried out expeditiously and economically. Furthermore, the construction is efficient in the performance of its intended functions and also from the standpoint of water consumption, since with the type of rotor shown, 55 requisite power may be obtained with a minimum water consumption.

It will be noted, that the casing is of 60 substantially hour glass cross section and the rotor is also of substantially the same shape and they cooperate with a relatively close fit, just sufficient for proper clearance, so 65 that the corrugations of the rotor form with the walls of the casing pockets adapted to receive and contain water from the jets.

Thus after the force of the water has been spent, the weight of the water in these pockets will assist in rotating the rotor until said water is discharged at the bottom of the casing. If the said walls of the casing were 70 made flat and a rotor of substantially hour glass cross section positioned therein, the water which will simply flow by the rotor after the force of the water was spent and much of the power of the water to rotate the 75 rotor would be lost. With the construction shown in the drawings, however, maximum efficiency in water power is obtained.

The drawings illustrate the invention in its preferred practical form, but the invention is to be understood as fully commensurate with the appended claims.

Having thus fully described the invention, what I claim as new and desire to secure by Letters Patent is:

1. In a water motor, a rotor comprising a single disk radially corrugated to form vanes, a casing in which the rotor is mounted to revolve, and means for directing a stream of water in a substantially tangential direction against the corrugations of the rotor, said casing being shaped to substantially conform to the cross sectional shape of the rotor and being closely fitted with respect to the opposite faces of said 90 rotor to form with the vanes thereof pockets adapted to receive and contain the water directed against said vanes.

2. In a water motor, a rotor comprising a single disk radially corrugated to form vanes, a casing in which the rotor is mounted to revolve, and means for directing a stream of water in a substantially tangential direction against the corrugations of the rotor, said water directing means being operable 100 to direct the water against the blades in either of two opposite directions to determine the speed of rotation of the rotor, and manually operable means for controlling the position of the water directing means, said 110 casing being shaped to substantially conform to the cross sectional shape of the rotor and being closely fitted with respect to the opposite faces of said rotor to form with the vanes thereof pockets adapted to receive 115 and contain the water directed against said vanes.

3. In a water motor, a rotor embodying a single sheet metal plate radially corrugated to form vanes and of substantially hour glass cross section, and means for directing a stream of water against the vanes in succession in a substantially tangential direction for the purpose of imparting rotation to the rotor, means for controlling the 120 tangential direction of said stream of water to control direction of rotation of the rotor, and a casing enclosing said rotor and shaped to form with the vanes of the rotor pockets adapted to receive and contain water di 130

rected against said vanes in either direction.

4. In a water motor, a rotor embodying a plate radially corrugated to form vanes and of substantially hour glass cross section, means for directing a stream of water against the vanes in succession in a substantially tangential direction for the purpose of imparting rotation to the rotor, and a casing of substantially hour glass cross section enclosing said rotor to form with the corrugations pockets into which said water is received.

5. In a water motor, a sheet metal casing embodying a plurality of sheet metal sections secured together to form a casing of substantially hour glass cross section, said casing being provided with an inlet and an outlet, a radially corrugated sheet metal rotor of substantially hour glass cross section operable within the casing and closely fitting with respect thereto, a sheet metal shell associated with the inlet, yieldable means positioned within the shell for frictionally supporting the casing upon a faucet, and valvular means positioned within the casing for directing water entering the casing into engagement with the rotor in one direction or the other to impart rotation to the rotor in corresponding directions.

6. In a water motor, a rotor embodying a sheet metal plate provided with radial corrugations forming the vanes of the rotor, said corrugations being so formed that alternate vanes occupy planes substantially including the axis of the rotor, and means for directing a stream of water against said alternate vanes along an axis substantially perpendicular to said planes.

7. A rotor for water motors embodying a sheet metal plate provided with radial corrugations forming the vanes of the rotor, said corrugations being so formed that alternate vanes occupy planes substantially including the axis of the rotor.

8. A rotor for water motors embodying a sheet metal plate provided with a substantially flat central portion centrally perforated to mount the rotor on a shaft, and which plate is radially corrugated between the substantially flat central portion and its outer circumference to form a succession of vanes, said corrugations being so formed that alternate vanes occupy planes substantially including the axis of the rotor.

In testimony whereof, EDWIN S. BROTHERS has signed his name to this specification this 15th day of May, 1926.

EDWIN S. BROTHERS.
